FLOAT VALVE

William A. Reinhardt, Ashland, Wis.

Application July 13, 1931, Serial No. 550,460

4 Claims. (Cl. 137—104)

This invention relates to float valves and particularly to operating mechanism therefor.

Float valves now in common use in toilet flush tanks ordinarily respond directly to the action of the float causing a slow approach of the valve to its final closing position as the water level approaches a predetermined height. This results in a gradual throttling of the flow through the valve causing wear and producing objectionable noise.

Attempts heretofore made to overcome this condition have not proven entirely successful. Efforts along this line have included a main float and auxiliary float associated in such manner that the valve is retained in fully opened position until the ultimate water level has been reached, whereupon the main float is released to thereby effect a sudden closing of the valve. Such a system is objectionable in that it requires the use of two floats and for the additional reason that it causes hammering in the supply pipes as the result of the sudden change in flow from a full flow to an instantaneous no flow condition. Other systems designed for this purpose have not been sufficiently positive in their action to insure proper functioning.

An object of the present invention is the provision of an improved float valve operating mechanism which will interrupt the closing action of the valve at a predetermined point, and which will positively lock the valve against further closure until a proper water level has been obtained, and to thereupon complete the closing action substantially instantaneously.

Another object is the provision of mechanism having the above described characteristics which may be readily adjusted to accommodate the action to various operating conditions.

Other objects and advantages will appear from the following description of an illustrative embodiment of the present invention.

Figure 1 is a view in side elevation of a float valve and operating mechanism therefor constructed in accordance with the present invention.

Fig. 2 is a similar view showing the parts in a different position.

Fig. 3 is a fragmentary top plan view of the device shown in Figs. 1 and 2.

The float valve selected for illustration includes a valve element 10 of a well known type commonly employed in toilet flush tanks, vertically movable to control communication between a supply pipe 11 and a discharge pipe 12. When in the lower position of Fig. 2 the valve element

10 blocks communication between pipes 11 and 12, and when in elevated position permits flow therebetween. The valve shown also includes the usual system of actuating levers including a lever 13 rockably supported intermediate its ends upon a pivot pin 14. The lever 13 is actuated by the usual ball float 15 mounted on a rod 16, which is connected to the lever 13 through a resilient connection which will permit movement of the ball relative to the lever 13.

The resilient connection just mentioned may assume various forms, but in this instance comprises a narrow rod, preferably of spring steel, bent upon itself to form two parallel portions 17. Both portions 17 of the resilient rod are fixed to the end of lever 13 by an appropriate clamp plate 18, and carry a plate 19 having a lug 20 in which the end of the float rod 16 is fixed. The plate 19 is preferably adjustably fixed to the rod portions 17 by appropriate means such as a clamp plate 21.

The plate 19 also carries a bracket 22, preferably extending upwardly therefrom, and provided with a pair of ears 23 between which a latch element 24 is rockably mounted. A hinge pin 25 supports the latch. The latch is provided with a tapered head 26 at the lower end thereof provided with a tooth 27 for coaction with a stationary stop lug 28 to interrupt the upward movement of the resilient rod during the downward closing movement of the valve. The upper end of the latch is preferably guided between a pair of guide members 29 formed on the bracket 22.

The latch 24 is positioned by a stop screw 30 carried by the bracket 22 and provided with a lock nut 31. A spring 32 acts on the latch 24 in such direction as to yieldably retain the same in definite position against the end of the stop screw.

With the parts in their respective positions illustrated in Fig. 2, the valve element 10 is held in its lowermost position due to the elevated condition of the float and the consequent action of the spring rod 17 on the lever system connected with the valve element. The valve is closed when in this position. When water is withdrawn from the tank the lowering movement of the float is transmitted through the rods 16 and 17 in the usual manner to effect opening of the valve, and during this action the head 26 of the latch passes and clears the stop lug 28, the latch being permitted to swing against the pressure of the spring 32 to permit such passage.

Then during refilling of the tank the ball float

rises, moving the valve element 10 downwardly toward closing position until this movement is interrupted by the interlocking engagement of the tooth 27 of latch 24 beneath the stop lug 28. 5 When this occurs further movement of the valve element is positively prevented but the float continues to rise under the buoyant action of the water and in so doing deflects the resilient rod 17 upwardly. This deflection of the rod, transmitted to the latch through the stop screw 30, causes the latch to swing in such direction as to withdraw tooth 27 laterally from beneath the lug 28. As the latch is thus released the spring rod 17 recoils and instantly acts through the 10 lever 13 to effect instantaneous and complete closing of the valve. Thereafter, the elevated condition of the ball float maintains sufficient tension in the rod 17 to retain the valve against its seat. The degree of residual tension thus 15 remaining in the rod 17 is determined by proper setting of the stop screw 30, since the setting of that screw determines the degree of deflection of the rod 17 required to release the latch, and thereby determines the water level at which the 20 latch will release.

Further regulation of the latch mechanism may be had by adjustment of the bracket 22 lengthwise of the rod 17.

From the foregoing it will be noted that mechanism has been provided by which a float operated valve is interrupted at a predetermined point in its closing movement, and whereby its final closure is effected substantially instantaneously, to thereby eliminate the wear and objectionable noise incidental to a slow closing action, and in such manner as to prevent hydraulic hammering which might otherwise result from an abrupt change from full open to full closed position. It will also be noted that the mechanism described provides an accurate adjustment for predetermining the water level at which final closing of the valve occurs, so as to insure sufficient level to maintain the valve in closed position against various water supply pressures.

45 Various changes may be made in the embodiment of the present invention hereinabove specifically described without departing from or sacrificing the advantages of the invention as defined in the appended claims.

I claim:—

1. In a device of the character described the combination of a valve, a float for operating the same, a resilient flexible connection between said float and valve through which said valve is actuated, latch mechanism for releasably holding said valve against final closing, and means responsive to the flexing of said connection for releasing said mechanism to thereby permit said valve to close. 5

10 2. In a device of the character described the combination of a valve, a float for operating the same, a resilient flexible connection between said float and valve through which said valve is actuated, a latch carried by said connection for releasably holding said valve against final closing, 20 and adjustable means responsive to the flexing of said connection for releasing said latch to thereby permit said valve to close.

25 3. In a device of the character described the combination of a valve, a float for operating the same, a resilient flexible connection between said float and valve through which said valve is actuated, a pivoted latch carried by said connection operable to interrupt the closing action of said valve, an adjustable stop screw, responsive to the flexing of said connection for releasing said latch to thereby permit said valve to close. 30

35 4. In a device of the character described the combination of a valve, a float for operating the same, a resilient operating connection between said float and valve, a bracket adjustably mounted on said connection, a latch pivotally mounted on said bracket and operable to interrupt the closing action of said valve, and an 40 adjustable element on said bracket responsive to deflection in said resilient connection for releasing said latch to thereby permit said valve to close.
